UNITED STATES PATENT OFFICE

2,522,869

GAUGE AND CORE FOR STEREOTYPE
MOLD BOXES

Stephen I. Griglak, Manassas, Va.

Application March 8, 1949, Serial No. 80,207

1 Claim. (Cl. 22—5)

1

My invention relates to improvements in mold boxes for molding stereotype plates, and more particularly to attachments for such boxes. The mold box and attachments disclosed herein-after are specifically adapted for the molding of stereotype plates of a width for either one or two columns of newspaper space, but obviously may be utilized for other types of stereotype plates. Conventional mold boxes for stereotype plates include a flat bed adapted to support the matrix, a lid having a flat inner surface adapted to be clamped to the bed, and type-high side bearers comprising gauges for spacing the lid from the bed a distance equal to the thickness of the mold or plate desired. In such mold boxes, the molded plate is substantially thick and heavy and requires considerable work and effort to carry the same from place to place. Moreover, when a number of such plates are placed in a printing form, it increases the weight of the form substantially. Also, such thick plates normally have to be trimmed for use and require considerable work to trim them to the proper size for use. I am aware that mold boxes have been made wherein the inner surface of the lid has formed thereon or detachably secured thereto by screws or otherwise cores for forming recesses in the back of the plate, whereby to lighten the same. However, these structures are expensive and are especially designed for casting plates of a fixed measure. Thus, where the user must cast a plate of a size considerably smaller than the interior of the mold box, such boxes cannot be used and a conventional box must be used instead. Alternatively, the printer would have to have a separate mold box for every size of plate to be cast. Also, such devices necessitate the use of hold-downs for the molded plate to prevent distortion of the same when the lid and attached cores are lifted and the molded plate sticks to the cores.

With the foregoing in view, it is an object of my invention to provide an improved mold box for stereotype plates.

A further object is to provide an improved type-high side bearer for use with conventional mold boxes for stereotype plates.

A further object is to provide an improved core for use with conventional mold boxes for stereotype plates.

A further object is to provide an improved combination of type-high side bearers and cores for stereotype mold boxes.

A further object is to provide an improved pair of type-high side bearers for use in stereotype mold boxes, which side bearers include in-

2

wardly-projecting portions providing cores disposed in longitudinally-overhanging relation to the bed of the box and/or an improved removable core for a stereotype mold box together with novel means for supporting the removable core in a proper position inwardly of the mold box and in overhanging relation to the bed thereof.

Other objects and advantages reside in the particular structure of the device, combination and arrangement of the several parts thereof, and will be readily understood by those skilled in the art upon reference to the attached drawing in connection with the following specification, wherein the invention is shown, described and claimed.

In the drawing:

Figure 1 is a plan view of an improved removable core for use in a stereotype mold box;

Figure 2 is a side elevation thereof;

Figure 3 is a bottom plan view thereof;

Figure 4 is a view like Figure 2, but on a reduced scale and showing the core in position in the mold box, the mold box being shown in longitudinal vertical section;

Figure 5 is a fragmentary transverse vertical sectional view on a greatly enlarged scale showing the removable core in position in the mold box;

Figure 6 is a plan view of a type-high side bearer for use in a stereotype mold box;

Figure 7 is a side elevational view thereof;

Figure 8 is a bottom plan view thereof;

Figure 9 is an end elevational view thereof looking in the direction of the arrow 9 of Figure 6;

Figure 10 is a transverse vertical sectional view on a greatly enlarged scale showing the use of the side bearers of Figures 6 to 9, inclusive, in a stereotype mold box;

Figure 11 is a view like Figure 10 on a reduced scale and showing the use of a slightly different form of removable core.

Figure 12 is a fragmentary transverse vertical sectional view showing an alternative way of using the side bearer of Figures 6 to 10, inclusive.

Referring specifically to the drawing, wherein like reference characters have been used throughout the several views to designate like parts, and referring at first to Figures 4, 5, 10 and 11, 12 designates generally a conventional mold box for stereotype plates, which box includes a bed 13 having a flat upper surface 14 adapted to support a matrix 19 thereon. The mold box 12 includes a lid 15 having a flat under surface 16.

The lid is adapted to be clampingly secured to the bed 13 by any suitable clamps 17 pivoted to either the lid or the bed by any suitable pivots 18. Figure 5 illustrates the lid 15 spaced from the bed 13 by conventional type-high side bearers 20, only one of which is shown. As so far described, the structure is conventional and forms no part of my invention.

Referring now to Figures 1 to 5, inclusive, 21 designates generally a removable core for use with the conventional mold box aforesaid. This form of removable core is adapted for use with mold boxes for casting stereotype plates having the width of one newspaper column. The core 21 comprises a type-high bearer portion 22, one end of which has fixedly secured thereto or integral therewith, as shown, an elongated core portion 23. The free end of the core portion 23 may be beveled as shown at 24, and is intended to abut a type-high side bearer 25, Figure 4, closing one end of the mold box. The bearer portion 22 and core portion 23 have flush top surfaces 26 complementary to the inner surface 16 of the lid 15 of the mold box. The bearer portion 22 has an under surface 27 formed with a transverse rocker portion 28. In the embodiment illustrated, the under surface 27 is beveled rearwardly and upwardly to provide a forwardly-located knife edge 29 which bears upon the upper surface 14 of the bed 13, or rather, upon the upper surface of the matrice 19. The bearer portion 22 also has the rearward extension 29 integral therewith which interfits with any suitable handle 30 of heat-insulating material, and which is secured thereto by any suitable means, such as the machine screws 31, Figure 1.

In use, the removable core 21 is preheated in any suitable manner to substantially the temperature of the molten-type metal to be cast into the mold. The core is then inserted in the mold longitudinally thereof with the rocker 28 resting atop the matrice 19. Obviously, the weight of the core portion 23 will cause the same to sag downwardly, whereby to project the rear portions of the bearer portion 22 upwardly. However as soon as the lid 15 is clamped into place, the bearer portion 22 will be rocked on its rocker 28 and the upper surface 26 of the same and of the core portion 23 will be forced tightly against the sheet 40 and under the surface 16 of the lid 15. This arrangement prevents type metal from getting on top of the core portion 23. Also, this ensures against slight irregularities permitting a loose fit of the core portion in the mold box. Preferably, the said core portion 23 is highly polished to minimize chances of engagement with the type metal. This desirable feature is enhanced by the preheating of the core portion 23, whereby the same is readily removed from the cast plate after the lid 15 has been raised. While, as shown, the removable core 21 is usable with standard type-high side bearers 20, as shown, I prefer to use it with type-high side bearers now to be described and best seen in Figure 6 to 10, inclusive.

As there illustrated, I have provided a pair of complementary type-high side bearers 33 and 34 for the left and right-hand sides, respectively of the mold box 12. As the bearers 33 and 34 are substantially identical, only one will be described in any great detail. Thus, the left-hand side bearer 33 comprises a type-high side bearer portion 36 adapted to be clamped between the lid 15 and bed 13 in a conventional manner. However,

such side bearer 33 is formed with an undercut inner side providing an elongated core portion 35 which projects inwardly of the mold box in overhanging relation to the bed and matrix. The side bearers 33 and 34 are, of course, formed of highly polished material and are adapted to be preheated to substantially the temperature of the molten type. Also, I prefer that the rear end of each side bearer have a handle 37 of the same material formed integrally therewith. Thus, the handling of the side bearers is facilitated. The right-hand side bearer 34 likewise includes a side bearer portion 36' and an overhanging core portion 35', which, except for the reversal of the location of the parts, is identical to the side bearer 33. As is apparent from Figures 10 and 11, the side bearers 33 and 34 supplement the removable core 21 and provide recesses in the back of the stereotype plate, whereby to lighten the same and also reduce the thickness thereof at the side edges, whereby to facilitate the trimming of the plate to a proper width. As shown in Figure 12, where it is desired to form the plate with side edges of full thickness, as would be the case with the customary side bearers 20 of Figure 5, the operator need only reverse the side bearers 33 and 34 so as to present the bearer portions 36 and 36' to the interior of the mold box.

Figure 11 illustrates a slightly modified form of removable core which is adapted for use in molding stereotype plates having a width equal to two newspaper columns. Thus, the removable core 41 there illustrated includes a type-high bearer portion 42 and an integral core portion 43 which is substantially wider than the corresponding core portion 23 of the first-described removable core. Likewise, it should be understood that the bearer portion 42 includes a transverse rocker which may be similar to the rocker 28 of the first-described form and which functions in the same manner. Obviously, removable cores of other configurations for wider cuts may be formed within the scope of the invention.

In all forms of the invention, the sheet 40 of heavy paper or cardboard is interposed between the inner surface 16 of the top 15 and the bearing surfaces of the members 20, 21, 25, 33 or 34 or 41. The purpose of the sheet 40 is, of course, to prevent the type metal from sticking to the surface 16 of the cover or top 15.

It is contemplated that the cores 21 or 41, as well as the side bearers 33 or 34, may come in a variety of sizes. Thus, although a single pair of side bearers 33 and 34 may be utilized continuously with a different box, it might be necessary to use a plurality of cores 21 or 41 and/or cores of larger or smaller size than those illustrated. Likewise, it might be desirable to use two or more cores 21 or 41 in the same box in certain circumstances. Moreover, the use of such cores 21 or 41, or variations thereof, gives great flexibility to a standard stereotype box, in that it enables the printer to cast plates of any size within the dimensions of the box, and to form a recess in the back end or side edges of the plate so molded irrespective of its size.

Thus, while I have shown and described what is now thought to be the preferred embodiments of the invention, it is to be understood that the same are susceptible of other forms and expressions. Consequently, I do not limit myself to the precise structures shown and described hereinabove except as hereinafter claimed.

I claim:

An elongated removable core for use with a

stereotype mold box having a flat bed for supporting a matrix and a lid provided with a flat inner surface, said core comprising an elongated generally rectangular bearer portion engaging between the bed and lid and having a flat top surface and a slightly longitudinally inclined bottom surface arranged at a slight angle to the top surface of the bearer portion and flat inner surface of the lid, one end of the bearer portion being slightly taller than the opposite end thereof, the bottom surface of the bearer portion terminating at the taller end thereof in a transverse substantially sharp edge about which the core rocks, and an elongated core portion secured to the taller end of the bearer portion and extending longitudinally of the bearer portion and engaging between the bed and lid, the core portion having a flat top surface substantially flush with the flat top surface of the bearer portion, the bottom of the core portion being transversely rounded and spaced above said transverse edge throughout the entire length of the core portion for forming a clearance space between the bot-

tom of the core portion and bed, whereby when the lid is closed the core rocks upon the transverse edge of the bearer portion and the top surface of the core portion swings into positive engagement with the flat inner surface of the lid.
